LOCK STITCHING ATTACHMENT

Joseph A. Sommers and Milton Friedman,
Philadelphia, Pa.

Application June 14, 1933, Serial No. 675,851

3 Claims. (Cl. 66—97)

Our invention relates generally to knitting machines of the circular type, and particularly to an attachment for a conventional circular knitting machine enabling the forming of fabrics of non-running character through the incorporation of lock stitches in the fabric at selected points; and an important object of our invention is to provide a simple and effective attachment of this type enabling the production of a novel non-running fabric, the attachment being simple, inexpensive, and easily installed and maintained.

Other objects and advantages of our invention will be apparent from a reading of the following description in connection with the drawings, wherein for purposes of illustration we have shown a preferred embodiment of our invention.

In the drawings:—

Figure 1 is a top plan view of a circular knitting machine, showing a pair of units constructed and applied to the machine in accordance with the principles of our invention.

Figure 2 is a transverse vertical sectional view through a portion of the needle cylinder showing the construction and arrangement of one of the units.

Figure 3 is a top plan view of a portion of the unit showing the cooperation of needle operating wheels with needles.

Figure 4 is a vertical transverse sectional view through Figure 2 showing an operative position of a pair of needles having a stitch carried thereby.

Figure 5 is a transverse vertical sectional view through Figure 3 showing an operative position of a pair of needles.

Figure 6 is a top plan view of one of the operating wheels.

Figure 7 is an elevational view of the outside of the push down or stitch spreading wheel.

Figure 8 is a side elevational view of a plurality of the needles showing a pair thereof in the position first given them by the inside operating wheel.

Figure 9 is a view similar to Figure 8 showing the final operative position of said pair of needles given them by the outside operating wheel preliminary to be engaged by the push down or splitting wheel.

Figure 10 is a plan view of our novel fabric made by the attachment.

Referring in detail to the drawings, the numeral 5 refers generally to a conventional type of circular knitting machine having the table portion 6 whereon are mounted conventional feeds 7, 8, 9 and 10. The feeds act upon the needles generally designated 11 which are mount-

ed upon the rotating cylinder or needle carrier 12. It will be obvious that a suitable number of feeds may be employed, the pair of the attachment units 13, 14 being diametrically opposed or in any other suitable arrangement according to the number and disposition of the feeds.

Since the attachment units 13, 14 are exactly similar in form and arrangement, description of one of them will suffice to disclose the nature of the other.

Each of the units comprises an inside bracket 15 and an outside bracket 16. The brackets have stationary standards 17, 18 which have vertically adjustable members 19, 20 mounted thereon by a bolt disposed through a slot in the standard and a slot in the vertically adjustable member. The brackets 15, 16 are radially and circumferentially adjustable as a whole on the table 6 of the knitting machine, the bracket 15 being located radially inwardly of and the bracket 16 radially outwardly of and adjacent to the needle carrier or cylinder 21 and fastened in place with bolts passing through appropriate slots in the table. A third bracket 22 is located radially outwardly of the needle carrier 21 and radially inwardly of the bracket 16, and is adjustably connected with the table by a bolt engaging an appropriate slot in the table and supports a vertically adjustable member 23 connected thereto by a bolt traversing a slot therein and a slot in the member 23, a horizontal member of which carries in a vertical plane the push-down wheel which is generally designated 24 and which is located perpendicularly above the needles 11 as indicated in Figure 2.

The inside bracket 15 carries by its member 19 a vertical bearing 25 on which is operatively mounted the inside operating wheel 26.

The outside bracket 16 carries by means of its member 20 a vertical bearing 27 which rotatably carries the outside operating wheel 28 which is located above and slightly overhangs the inside operating wheel 26.

The operating wheels are identical in form, but inverted with respect to each other as indicated in Figure 2, and as shown in Figure 6, comprise a circular disk cut in its circumferential edge with large V-shaped notches 29 into the apex of each of which opens a small generally rectangular radially inwardly extending notch 30 adjacent pairs of the notches resulting in teeth 31 having substantially parallel sides with the radially outward ends thereof arranged in planes passing chordally through the wheel.

The push-down wheel 24, a portion of which is shown also in Figure 4, is illustrated in Figure 5

7 as comprising a circular disk having notches 32 cut in its circumferential edge which define substantially triangular teeth 33, into which notches 32 lead openings 34 on the inner side 5 of the disk, the openings 34 having substantially parallel sides and the triangular cross section indicated in Figure 4. Each of the various wheels is equipped with a suitable hub. It will also be observed that the radially outward ends 10 of the teeth on the inside and outside operating wheels are beveled, while the radially outward ends of the teeth on the push-down wheel 24 are straight.

The fabric of the invention is attained by 15 spreading the stitches in every alternate course so as to make a course of lock stitches. It is to be observed that the attachment of the invention does not change otherwise the operation of the 20 knitting machine in any manner. The spreading of the stitches is accomplished by the insertion between the knitting feeds 7, 8, and 9, 10 of the units 13, 14, which contain wheels which are run, that is rotated, by the engagement of the 25 rotating needle cylinder therewith. These wheels may be operated in any other position than that of the vertical and horizontal shown herein.

The operation of the attachment is as follows: While the needles 11 are travelling between the unit 13 and the unit 14, two courses of regular 30 stitches are made by the units 8 and 9 as will be evident. The wheels 26, 28 and 24 have the same pitch and the teeth the same spacing as the needles 11. The inside operating wheel 26 is so adjusted that two of the needles at a time 35 are engaged by the large V-shaped notch 29 thereon and are thereby bent out of the true vertical, and by means of the small parallel side slot 30 the same pair of needles is still further bent out of the vertical and into the position 40 shown in Figure 9 from that shown in Figure 8. The position of the yarn at this juncture, that is in the position of the needles shown in Figure 9, is clearly illustrated in Figure 4. While the pair of needles mentioned is still in the position 45 shown in Figures 9 and 4 they are engaged by the push down wheel 24 and the teeth thereof depress the stitch 35, so that upon release of the pair of needles by the wheel 24 they spring back to their initial position, whereby half of the 50 stitch originally on the first needle to engage the units 13 and 14 is transferred to the immediately following needle of the pair, so that the immediately following needle will then carry one and one-half stitches.

55 When released from engagement by one of the spreading units, the needles having returned to their initial positions resume their travel through the next succeeding ordinary feeds toward the remaining spreading unit of the attachment, the 60 stitches described being held below the heads of the needles by any suitable guide means. In the transit between the spreading units, two regular courses of stitches are made, the first to clear the non-run stitch, and the second course to be 65 split by the second spreading unit with the following variation. The first needle of the said pair having engaged and passed through the first spreading unit, carries one and one-half stitches, and the succeeding needle only one-half 70 stitches, and of a stitch. In order to obtain a uniform fabric, the operating wheels and the push-down wheel of the second spreading unit are so adjusted that upon arriving thereat, the last regular stitch on the said needle carrying the extra half stitch is 75 picked up and spread and one-half of a stitch is

transferred to the next succeeding needle on the cylinder. That is to say, the first needle and the following needle are acted upon by the first spreading unit, and the said following needle and the next succeeding needle, that is, a third needle, 5 are acted upon by the second spreading unit, and at the next half revolution of the needle carrier, the said third needle and a next succeeding or fourth needle are acted upon in the manner described in connection with the first and second 10 needles, the operation of spreading the stitch being repeated on each pair of adjacent needles.

Starting at any given point on the circumference of the needle carrier the first needle to engage the unit 13 may properly be referred to as 15 the first needle, for purposes of describing the knitting cycle. The second, third, fourth, etc. needles are then so called by reference to this first needle according to their order in following the first needle. On the first engagement, the 20 unit 13 spreads the stitch on the first needle over and onto the second needle. Then two plain courses are knitted on the units 8 and 9. On the second plain course the unit 14 spreads the stitch of the second needle over and onto the third 25 needle. This process and sequence is repeated throughout the knitting operation of the machine.

The inside and outside operating wheels 26, 28, respectively, are as already stated, identical in 30 design, the inside wheel 26 being reversed with respect to the outside operating wheel in order to bring the upper side of the teeth in contact with the needles as shown in Figure 2. The inside wheel 26 is shown as operating below the 35 outside wheel 28 and as close to the operating teeth the outside wheel as possible.

It will be noted that it is essential to maintain the position of the needles of the said pair, that is, the first and second needles, the second and 40 third needles, and the third and fourth needles, etc. brought into being by the inside operating wheel 26 until the new position obtained by the operation of the outside wheel is arrived at, thereby by making the movement of each pair of adjacent needles continuous from the normal position to the spreading position shown in Figures 9 and 4. It is to be noted that in present knitting machines making a lock or non-running stitch, the stitch is usually obtained by bringing the machine to a dead stop and accomplishing the operations by means of pickers or similar devices to make a change in the stitching, whereas in the device of the invention continuous operation of the machine is not interfered with, so that considerable increase in the productivity of the machine, and considerable economy of power and labor is effected, together with an increase in the uniformity and perfection of the resulting fabric.

Although we have shown and described herein 55 a preferred embodiment of our invention, it is to be definitely understood that we do not desire to limit the application of our invention thereto, and any change or changes may be made in material and structure and arrangement of parts, 60 within the spirit of the invention and the scope of the subjoined claims.

What is claimed is:—

1. A lock stitch imposing attachment for a conventional circular knitting machine having a 70 pair of plain course forming feeds and a rotatable carrier equipped with circumferentially spaced vertically arranged needles; said attachment comprising a unit disposed adjacent said carrier and between said feeds; said unit comprising an out- 75

side pairing wheel, an inside pairing wheel, and a push down wheel cooperating with said outside and inside wheels, the latter wheels having their peripheries formed with means to engage two succeeding needles as the carrier is rotated and dispose one of these needles in back of the other so that the beards of the needles remain open and the stitch on one needle can be spread over and onto a succeeding needle of said carrier, said push down wheel having its periphery formed with second means to engage the two needles disposed as stated in a manner to spread the stitch over and down along the two needles whereby a spread locked stitch is produced on alternate needles of said carrier.

2. A lock stitch imposing attachment for a circular knitting machine and including a pair of plain course forming feeds and a carrier equipped with circumferentially spaced vertically arranged needles, said attachment comprising a unit disposed adjacent said carrier and between said

feeds, means to engage two succeeding needles and dispose one of these needles in back of the other so that the stitch on one needle can be spread over and onto the said two needles of said carrier, said means spreading the loops on the pair alternately.

3. A lock stitch imposing attachment for a circular knitting machine and including a pair of plain course forming feeds and a carrier equipped with circumferentially spaced vertical arranged needles, said attachment comprising a unit disposed adjacent said carrier and between said feeds, means to engage two succeeding needles and dispose one of these needles in back of the other so that the stitch on one needle can be spread over and onto the said two needles of said carrier, said means spreading the loops on the pair alternately, and a notched push down wheel geared to the needles.

JOSEPH A. SOMMERS. 20
